UNITED STATES PATENT OFFICE.

WILLIAM M. McCOMB, OF NEW YORK, N. Y.

APPARATUS FOR CONVERTING HIGHER-BOILING-POINT HYDROCARBON OILS INTO LOWER-BOILING-POINT HYDROCARBON OILS.

Application filed March 2, 1921. Serial No. 449,153.

To all whom it may concern:

Be it known that I, WILLIAM M. McCOMB, a citizen of the United States, residing at New York, in the county and State of New York, have invented certain new and useful Improvements in Apparatus for Converting Higher-Boiling-Point Hydrocarbon Oils into Lower-Boiling-Point Hydrocarbon Oils, of which the following is a specification.

This invention relates to a new and improved apparatus for carrying out a process of dissociating higher boiling point hydrocarbons and water into other forms of hydrocarbons and their constituent elements and reassociating the same into lower boiling point hydrocarbons, wherein the various hydrocarbon compounds are first progressively heated, and while being heated or vaporized, are intimately associated and commingled with the aqueous vapors of the water and are afterward dissociated and reassociated in a manner substantially as hereinafter described.

The present invention contemplates the provision of an apparatus particularly adapted to carry out the process covered in my Patent No. 1,337,144 dated April 13th, 1920, and also the process covered by my Letters Patent No. 1,374,858, and although it will be understood that the apparatus to be hereinafter described is adapted to carry out other similar processes or modifications of the processes of my aforesaid patents it is nevertheless primarily adapted for the carrying out of the said last two mentioned processes.

One of the principal objects of the present invention is to provide new and improved means whereby the various degrees of heat, to which the hydrocarbon compounds and aqueous vapors are subjected, in their travel through the converting coil or vessel, may be regulated to a greater nicety than it has been possible to regulate them in apparatus as hitherto constructed.

Another object of the invention is to simplify the construction of apparatus of this character, reduce the size of the apparatus and insure greater safety of operation.

A further object of the invention is to provide an apparatus of the above character wherein a product of a more uniform character or quality can be produced than it has

been possible to obtain by the use of apparatus hitherto designed to accomplish analogous purposes.

Other objects and aims of the invention, more or less specific than those above enumerated, will be in part obvious and in part pointed out in the course of the following description of the invention, and the scope of the protection contemplated will be indicated in the appended claims.

In the accompanying drawings wherein I have shown a preferred form of embodiment of my invention:

Figure 1 is a view in elevation, partly in section, illustrating the same.

Figure 2 is an elevational view of one of the hydrocarbon and aqueous vapor converting units.

Figure 3 is a view similar to Figure 2, showing in a diagrammatic manner the means of applying the heat to one of the converting units and the means for determining the degree of temperature to which the various parts thereof is being subjected.

Figure 4 is a cross-sectional view taken through the converting tube or vessel, for instance, on the line 4—4 of Figure 3.

Figure 5 is a top plan view showing the manner of conducting the converted material into the condenser.

Figure 6 is a top plan view of one of the pipes or conduits employed to conduct water to the converting tubes or vessels.

Figure 7 is a schematic view showing a converting tube or vessel associated with a diagram plotted to scale, showing as coordinates the several average boiling points of the material to be treated, and the percentages of such materials that vaporize at each particular temperature.

Similar reference characters refer to similar parts throughout the several views of the drawing.

Before proceeding with a description of the particular construction of this form of embodiment of my invention, it may be noted that hitherto in apparatus employed for oil conversion, no attempt has been made to provide means whereby the material in conversion in its passage through the converting coil will be subjected to such temperatures that the oil at a point adjacent the inlet end of the coil will be heated to a point

approximating the initial boiling point, that the temperature of the oil at a point adjacent the outlet end will approximate the end boiling point, and that the temperature of the oil at intermediate points in the coil will increase approximately in the same ratio through the total intervening length of the coil as the boiling point temperatures of the oil increase in ordinary fractional distillation of a sample of the oil under treatment throughout the successive temperatures of its boiling point range, or in other words, to produce an apparatus which will operate in the most scientifically perfect, and economical manner to convert heavy or higher boiling point hydrocarbon into lighter hydrocarbons or hydrocarbons having lower boiling points whereby there will be a relatively greater recovery of commercial or usable lighter boiling point hydrocarbons with a minimum production of fixed gases and losses through carbon deposits.

In the apparatus, one embodiment of which I shall now describe, I attain these and other important ends.

Referring now to Figure 1 of the drawings, the reference numeral 1 denotes a suitable base, upon which the various heating units, presently to be described, are supported, said base in the present instance supporting a casing 2, the latter being preferably divided into a plurality of compartments 3, 4, 5 and 6 by the partitions 7, 8 and 9.

Located in each of the said compartments is a converting tube or vessel, and inasmuch as said tubes or vessels are similar in all respects, a description of one of them will suffice to impart a clear understanding of this feature of construction, such tubular vessels being designated 10, 11, 12 and 13.

Each tubular vessel is formed by a tube of uniform diameter bent or turned into a hollow column, providing a downwardly pitched avenue of flow for the liquid to be converted from the top to the bottom of each coil. Preferably the pitch of the tubular structure is increased in a downward direction.

In this embodiment of my invention, I position upon each of the tubes a plurality of independent electric heating units, each unit comprising an independent coil, each coil being connected with a source of current supply, as indicated in the drawings; by means of the leads *a*, *b*, *c*, *d*, *e*, *f* and *g*, suitable rheostatic devices 14 being provided whereby the temperature of each of said coils may be independently regulated.

These electric heating coils separate the converting tubes or coils into a plurality of zones, that a gradually increasing temperature may be given to said converting coils from the top to the bottom thereof, it being desired to so heat the converting tubes or

coils that the temperature within the same at the top thereof approximates the initial boiling point of the material under treatment, the temperature of the material within the coil at a point adjacent the hottest or cracking point or zone approximating the end or highest boiling point of the volatile elements of the material being treated, and the temperature of the intermediate points of the coil increasing from the coolest part or zone at the top of the furnace approximately in the same ratio with respect to the total intervening length of said coil as the boiling point temperatures of the hydrocarbon oil being treated increase in ordinary fractional distillation, as determined by a sample of the oil under treatment throughout the successive portions of its boiling point range.

Where I have used the term "boiling point" in referring to the material under conversion, it is understood, of course, that I refer to boiling points of the hydrocarbon constituents under pressure, which boiling points are of course much higher than they would be at atmospheric pressure.

Referring now to the method I adopt in arriving at the length of each of the various zones, and the degree of heat to be maintained in each of said zones, I first determine by ordinary methods the boiling point characteristics of the given class of hydrocarbon oils to be treated. This I accomplish by carrying on fractional distillation operations upon several samples of the class of oils to be treated. Having determined the boiling point characteristics of the oil as aforesaid, I next plot, in a suitable manner, a diagram to scale, showing as co-ordinates the several average boiling points and the percentages of the materials that vaporize at each particular temperature.

Such average or composite boiling point curve shows the average proportionate quantity of such material that boils at the various temperatures within such boiling point range, that is to say, between the initial boiling point and the dry end or final boiling point. Such a plotted scale, and its relation to the converting tube or vessel, is shown in Figure 7 of the drawings, which has been plotted from an oil distillate having an approximate boiling point range between 450° F. and 850° F. 32° Baumé gravity, the curve 15 representing the average boiling point characteristics of several tested samples of oil having the above described characteristics. It will be noted that in this embodiment of my invention I have divided the converting coil or tube into seven (7) zones, each of which is supplied with an independent heating coil. Referring now to Figure 4 of the drawings, it will be noted that the tube 16 is surrounded by a coating or layer of insulat-

ing material 17, such for instance as mica, that the heating or resistance wire 18 is positioned about said insulating layer 17, and a layer of insulating material, such as mica, 5 19, is positioned about the resistance wire 18.

The composite tubular structure thus formed is then positioned within one of the compartments 6, which is then filled with a body of non-conducting high heat resisting 10 material 20, such for instance as asbestos.

The hydrocarbon material to be converted is drawn from a suitable reservoir 21, by means of the pump 22, and forced by means of said pump through the conduit 23, 15 through the condenser or preheater 24, the conduit 25, to a distributing chamber or reservoir 26, from which lead the conduits 27, 28, 29 and 30. The conduit 27 leads to the coil 18, the conduit 28 leads to the coil 12, 20 the conduit 29 to the coil 11, and the conduit 30 to the coil 10, each of said conduits being independently valved, as indicated generally at 31, and at this point it may be noted that I preferably employ a plurality of valves 25 in each conduit, so that the supply of hydrocarbon material to each of the converting vessels may be regulated to a nicety. A preferable arrangement of these valves, is to have them of different size, the valves with 30 the larger orifices being disposed nearest the source of supply.

The reference numeral 32 indicates a pump, which is adapted to draw water from any suitable source of supply, and pump 35 the same through a coil 33, which may be suitably heated as by means of the burner 34. The heated water passes from the coil 33 through the conduit 35, whence it passes through the conduits 36, 37, 38 and 39, to 40 the several converting tubes or coils.

In order that the supply of water to each of the converting vessels may be accurately regulated, I form each of the conduits 36 to 45 39 inclusive, as indicated in Figure 6 of the drawings, that is to say, I divide each of said conduits into a plurality of branches 40 and 41.

These branches spring from the fitting 42, and are again joined to the conduit 36 by 50 means of the fitting 43. Located in each of the branches 40 and 41 is a plurality of needle valves 44, 45, 46 and 47. The object of providing this construction, together with the valves and the branches is to provide a means whereby the discharge of water through the conduit may be accurately adjusted.

Conduit 35 is provided with a meter illustrated at 48, and each of the conduits 36 to 60 39 inclusive, are also provided with meters, indicated at 49. The conduit 36 leads to the coil 10, the conduit 37 to the coil 11, the conduit 38 to the coil 12, and the conduit 39 to the coil 13. Each of the coils 10 to 13 inclusive at its upper end is provided with a

fitting which forms a common means for conducting the hydrocarbon material and water into the upper end of the coil, it being preferable to discharge the hydrocarbon material into the coil at a point above the 70 avenue of flow of the water or aqueous vapors into said coil. These fittings are indicated in the drawings at 50.

Each of the coils 10 to 13 is provided with a pressure gauge, said pressure gauge being 75 illustrated diagrammatically at 51, whereby the pressure of the commingling hydrocarbon material and aqueous vapor may be determined at their point of entrance into the coils. Located in each of the zones of each 80 of the converting coils is a heat registering device, the same in the present instance being constituted of thermocouples, said thermocouples being indicated at 52, 53, 54, 55, 56, 57 and 58. It will of course be understood that if desired, such other number of these thermocouples may be provided in the converting tubes as may be necessary to aid in the determination and regulation of 85 the heat.

The hydrocarbon oil and water, or water vapor, as above described, are fed under pressure into the upper ends of the converting coils to the fittings 50, in the manner already described, the proportion of the 90 quantity of water to the hydrocarbon material to be converted to be fed into the coil being determined on the basis of the specific heat of the hydrocarbon material to be converted.

Located in each of the tubular converting coils and at the lower end thereof, is a body of high specific heat 59. This body may be formed of various materials heretofore utilized in a similar relation, such for instance 100 as nickle, chromium, or molybdenum, the coils being enlarged at these points to form chambers for the reception of these bodies of high specific heat. These bodies of high specific heat are, of course, located in the 110 lowermost or hottest zone of the converting coils.

Each coil at its lower end is provided with a fitting 60, from which leads 115 a conduit adapted to conduct the converted products to the condenser, said fitting 60 forming a housing for a heat measuring device, such for instance as the thermocouple 61, the latter extending into the lower end of the converting coil, so that the internal temperature in the vicinity of the body of high specific heat may be ascertained.

Referring now to the discharge of the 120 converted products from the converting coils or tubes, it will be noted that at the lower end of each tube is provided the hereinbefore mentioned conduits, said conduits being indicated in Figure 1 of the drawings, at 62, 63, 64 and 65, said conduits being formed 130

or curved or bent tubing, as shown, so as to avoid angles or fittings which would tend to obstruct the passage of the converted products.

5 Each of the conduits 62 to 65 leads into a tar trap, said tar traps being indicated at 66, 67, 68 and 69, and leading from the tar traps 66 to 69 inclusive, are the conduits 70, 71, 72 and 73, each being independently valved 70 as at 74. Conduits 70 to 73 inclusive lead into a common fitting 76 provided with a pressure gauge 77, and from this fitting 76 leads a conduit 78, the latter conduit leading to the preheater or condenser 24. The 15 condenser or preheating apparatus 24 consists of a series of concentric pipes, preferably disposed in the relation shown. Each length of the pipe is composed of an inner and outer conduit concentrically arranged 20 and spaced apart so that two continuous conduits are provided from one end to the other of the preheater or condenser. The raw material is forced through the outer conduit and is heated by the condensing converted material. In other words, the converted material is discharged through a conduit provided in the condenser, or from 25 heater 24, which is entirely surrounded by a conduit, through which is forced the raw material. This apparatus, therefore, forms 30 the double function of preheating the raw material and of cooling and condensing the converted material.

Each of the tar traps 66 to 69 inclusive 35 are provided with discharge conduits 79, which lead into a common discharge conduit 80, through which the tar is discharged into a tar tank not shown.

Leading from the condenser or preheater 40 24 is a conduit 81, through which the condensed converted material, together with the gases, pass into a receiving tank 82, said conduit 81 being preferably formed into branches 83 and 84, which lead through a 45 "look-box" 85, whence the gases and converted hydrocarbons are discharged into the said receiving tank 82. The conduit 81 is provided with a pressure gauge 86.

In the receiving tank the gaseous and 50 liquid products separate, the liquid products passing through the conduit 87 into the tank 88, where the converted hydrocarbon and water are separated, the hydrocarbon material passing through the conduit 89 to the intermediate storage tank 90, from 55 which leads the conduit 91. This last mentioned conduit conducts the finished converted product to a storage tank not shown.

The fixed gases pass from the chamber 82, 60 through the conduit 92, to the gas tank 93, whence they are discharged through the conduit 94 to the storage tank not shown.

I realize of course that many changes can 65 be made in the apparatus just described without departing from the spirit of my in-

vention, and it is to be understood that the matter contained in the above description and shown in the accompanying drawings shall be interpreted as illustrative only, and not in a limiting sense. The gas tank 93 is 70 maintained under a small vacuum by means of a suction blower not shown, the gauge 102 indicating the degree of vacuum attained.

Located in the branch conduits 83 and 84 75 are valves 95 and 96, which may be employed to regulate the pressure in the entire apparatus. There is also provided a valve 97 in the conduit 92 which may be employed for a similar purpose. The gauges 86 and 80 97 located in the conduits 81 and 92 respectively, register the pressure and determine the operation of the valves 95, 96 and 97.

A meter 99 is provided in the raw material conducting conduit 25 and a thermometer 100 is provided in the distributing box 26. Thermometers 101 are also provided in the conduits leading to each of the 90 converting coils so that the temperature of the ingoing oil and aqueous vapors or water may be determined.

Having thus described my invention, and the manner in which the same is performed, 95 what I claim as new and desire to secure by Letters Patent is:

1. In apparatus of the class described, in combination, a tubular continuous spiral coil arranged with its axis vertical for converting hydrocarbon material, the lower turns of the said coil having increased inclination to accelerate the passing material, and a plurality of electric heating units 100 operatively associated therewith.

2. In apparatus of the class described, in combination, a tubular continuous spiral coil arranged with its axis vertical for converting hydrocarbon material, the lower turns of the said coil having increased inclination to accelerate the passing material, and a plurality of independent electric heating units 110 operatively associated therewith.

3. In apparatus of the class described, in combination, a tubular spirally formed converting coil, the said coil having its axis vertically arranged and the lower turns of the coil having increased inclination to accelerate the passing material, and a plurality of independent electric heating units 115 positioned upon said coil.

4. In apparatus of the class described, in combination, a spirally formed converting coil, the said coil having its axis vertically arranged and the lower turns of the coil having increased inclination to accelerate the passing material, means for discharging hydrocarbon material and water into one end of said coil, and a plurality of electrical 125 heated coils positioned upon said converting coil.

5. In apparatus of the class described, in combination, a spirally formed converting coil, the said coil having its axis vertically arranged and the lower turns of the coil having increased inclination to accelerate the passing material, a plurality of independent electrical heating units mounted upon said coil, and means for regulating the amount of current supplied to each of said units.

6. In apparatus of the class described, in combination, a vertically disposed sinuously formed tube adapted for the conversion of hydrocarbon material, the lower portions of the tube having successively increased inclinations to accelerate the passing material, means for discharging said hydrocarbon material into the upper end of said chamber, means for discharging converted products from the lower end of said tube, and a plurality of independent electric heating units disposed one above each other upon said tube.

7. In apparatus of the class described, in combination, a converting unit for hydrocarbon material comprising a vertically disposed, spirally formed tube, the lower turns of the said tube being given greater inclination to accelerate the passing material, means for discharging a mixture of hydrocarbon material and water into the upper end of said tube, means for discharging converted hydrocarbon products from the lower end of said tube, a body of high specific heat located at the lower end of said tube, and a plurality of independently regulated electric heating units mounted upon said tube.

8. In apparatus of the class described, in

combination, a hydrocarbon material converting unit comprising a spirally formed, vertically disposed tube, the lower turns of the said tube being given increased inclination to accelerate the passing material, means for discharging measured quantities of hydrocarbon material and water into the upper end of said tube, means for conducting converted hydrocarbon material from the lower end of said tube, a body of high specific heat located in the lower end of said tube and disposed in the avenue of flow of the material under conversion, and a plurality of independent heating units mounted upon said tube and adapted to heat the contents of the latter to varying degrees of temperature, and also adapted to heat said body of high specific heat.

9. In apparatus of the class described, in combination, a plurality of heating units each comprising a coil, means for discharging measured quantities of water and hydrocarbon material into the upper end of said coils, a body of high specific heat located in the lower end of each of said coils and in the avenue of flow of the material under conversion, a single condenser for all of said converting units, means for discharging converted hydrocarbon products into said condenser, means for forcing the raw hydrocarbon materials through said condenser whereby the latter will be preheated by the condensation of the converted products, and means for electrically heating said converting units.

In testimony whereof, I affix my signature.

WILLIAM M. McCOMB.
